UNITED STATES PATENT OFFICE.

ELMER WISEMAN, OF MILWAUKIE, OREGON.

TACK-PULLER.

1,141,741.

Specification of Letters Patent.

Patented June 1, 1915.

Application filed March 10, 1914. Serial No. 823,775.

To all whom it may concern:

Be it known that I, ELMER WISEMAN, a citizen of the United States, residing at Milwaukie, in the county of Clackamas and State of Oregon, have invented new and useful Improvements in Tack-Pullers, of which the following is a specification.

This invention relates to tack pullers; and it has for its primary object the provision 10 of a simple device of this character which will consist of gripping devices mounted for relative movements and adapted to be effectually moved into gripping engagement with the head of the tack when pressure in 15 a downward direction is applied to the device.

Another object of the invention is the provision of a device of this character which will consist of relatively adjustable gripping devices and means for securing the devices in locked positions when engaged with the head of the tack and for subsequently releasing the members to permit the tack to be released from therebetween.

25 With these and other objects in view, the invention consists of certain novel features of construction, combination and arrangement of parts, as will be hereinafter described and claimed.

30 In the accompanying drawings:—Figure 1 is a longitudinal section through the device, showing the gripping members in their normal positions; Fig. 2 is a similar view, showing the gripping members in active 35 gripping positions; Fig. 3 is an inverted perspective view of the device; and Fig. 4 is a transverse section therethrough.

The device consists of a handle 1 which may be constructed of wood, metal or the like. The handle is provided with a bore 2 closed at one end, as at 3, and open at its opposite end, as at 4. Within the bore an extracting device 5 is mounted to slide in a longitudinal direction and it is preferred to 45 form this device from a single length of springy sheet metal bent upon itself to provide companion gripping members 6 and 6' which are provided with portions normally arranged in parallel relation to each other 50 and lying in the bore 2. The said members of the device are connected with each other by a curved upper portion 7, against which one end of a spring 8 is engaged. The opposite end of the spring bears against the 55 closed end 3 of the bore 2 and under the

action of the spring the device 5 is normally held in the position shown in Fig. 1.

A pin 9 extends through the handle and through the space between the members 6 and 6' and under the action of the spring 8 the portion 8 of the member 5 is normally held against said pin. As a consequence of this arrangement the member 5 is held against being entirely projected from the bore 2 of the handle 1.

65 The bore 2 is of substantially rectangular formation in transverse section and below the open end 4 of the bore the members 6 and 6' of the device 5 are respectively curved in opposite directions, as at 10 and they are 70 terminally provided with notches 11, which are adapted to embrace the shank of the tack. Under the inherent action of the metal from which the device is formed the bulged or curved portions 10 are adapted to 75 be normally extended or separated from each other for a distance to permit of their proper accommodation of the head of the tack. The said portions 10 are also extended laterally of the bore to such an extent 80 that when the device 5 is moved in a longitudinal direction toward the closed end 3 of the bore 2 the edges 12 of the walls of the bore will be brought to bear against the portions 10, so as to cause said portions to be 85 moved into gripping positions.

In using the device, the portions 10 are placed over the head of the tack. Pressure in a downward direction is then applied to the handle 1. When moving the handle in 90 this manner the surface 12 of the walls of the bore engage the portions 10 of the members 6 and 6' and the shank of the tack is thereby finally embraced by the notches 11. In order that the portions 10 may be locked 95 in this position during the extracting operation, the portion 10 of the member 6' is provided with a keeper slot 13 which is adapted to receive the effective locking end 14 of a pivoted dog 15. This dog is provided with 100 an extension 16 which is adapted to be engaged by the adjacent member 6' of the device 5, so that on movement of the handle 5 in a downward direction the end 14 will be made to spring into the keeper slot 13. 105 This dog is provided with a releasing lug 17, which extends through a passage 18 in the handle. This lug may be pressed by the hand and the dog may be rocked to cause the end 14 thereof to free itself from the 110

passage 13. Instantly on this operation the portions 10 of the members 6 and 6' of the extracting device will be returned to their normal extended positions under the action of the spring 8 and the device as a whole, thus set for a subsequent operation of extracting the tack. The lower end of the handle 1 is embraced by a metal ferrule 19 when the handle is constructed of wood.

10 I claim:—

In a tack extractor, a handle having a bore open at one end of the handle, a gripping element longitudinally movable in the bore and having a pair of spring projected jaws provided with cam portions bearing

against the sides of the bore at the open end thereof and coacting therewith to close the jaws when said gripping element is moved inwardly in the handle, a spring to project the gripping element from the open end of the handle, and a catch to lock the gripping element in the handle when in gripping, retracted position.

In testimony whereof I affix my signature in presence of two witnesses.

ELMER WISEMAN.
